United States Patent

Des. 239,947
Patented May 18, 1976

239,947

CIGARETTE HOLDER

Charles W. Frost, 7800 Wisconsin Ave.,
Washington, D.C. 20014

Filed May 14, 1974, Ser. No. 469,759

Term of patent 14 years

Int. Cl. D27—02

U.S. Cl. D27—7

FIG. 1

FIG. 2

FIG. 3

FIG. 4

FIG. 1 is a perspective view of a cigarette holder showing my new design;

FIG. 2 is a side elevational view thereof;

FIG. 3 is an end view looking toward the cigarette holding portion thereof; and

FIG. 4 is an end view looking toward the mouthpiece portion thereof.

I claim:

The ornamental design for a cigarette holder, as shown.
